UNITED STATES PATENT OFFICE.

JACOB WEBER, OF NEW YORK, N. Y.

CLOSURE FASTENER.

Application filed April 18, 1922. Serial No. 555,132.

To all whom it may concern:

Be it known that I, JACOB WEBER, a citizen of the Republic of Germany, and resident of New York, in the county of New York and State of New York, have invented certain new and useful Improvements in Closure Fasteners, of which the following is a specification.

One of the principal objects of this invention is to provide a bracket adapted to be attached to a window frame and window sash to hold the sash adjustably secured in a plurality of inclined ventilating positions.

Another object is to provide a bracket of this character which can be quickly and easily detached from the sash to allow the sash to be freely raised and lowered in the usual manner whenever desirable.

A further object is to provide a bracket of this character with means to effectually prevent the bracket from being detached from the sash when the sash is in any of the inclined positions and a further object is to improve upon the constructions of similar devices with which I am familiar by simplifying the construction, whereby the device may be manufactured and sold at a comparatively low price. With these and such further objects in view as will be apparent to those skilled in the art to which this appertains, the invention consists in the construction, combination and arrangement of parts herein specifically described and illustrated in the accompanying drawings, wherein is shown a preferred embodiment of the invention but it is to be understood that changes, variations and modifications may be resorted to which fall within the scope of the claims hereunto appended.

In the drawings forming a portion of this specification Fig. 1 is a fragmentary side view of a window frame with my improved bracket attached thereto, the sash being shown in full lines in an inclined ventilating position.

Fig. 2 is a detail side view showing the bracket in inoperative position and detached from the sash.

Fig. 3 is a front view of the parts shown in Fig. 2 showing the bracket attached to the sash, and

Fig. 4 is a detail perspective showing the sash fixture attached to the sash.

Fig. 5 is a perspective detail of the sliding head, and Fig. 6 is a detail.

Referring to the drawings 10 indicates

generally the window frame in which the upper and lower sashes 11 and 12 are mounted to slide in the slideways 13 and 14 respectively. The lower section 15 of the inner retaining strip of the slideway 14 is hinged as at 16 whereby it may be swung through an arc of 180° to allow the lower sash 12 to be moved to an inclined position as shown in full lines in Fig. 1 of the drawings. A bracket 17 is suitably secured to the frame 10 and carries at its lower end a headed pivot pin 18 which passes freely through a suitable aperture in an arm 19. The pin 18 is preferably secured to the bracket 17 by riveting and carries between the arm 19 and the bracket 17 a pair of washers 20 between which is mounted a lock washer 21. The lock washer 21 is placed under tension when the parts are assembled, thereby holding the arm upon its pivot with a firm but yielding frictional engagement.

The arm 19 is slotted longitudinally intermediate its ends as at 22 to provide a guideway for the reduced end 23 of a sliding head 24 which is slotted as at 25 to provide a pair of yoke arms 24' between which the reduced end of a link 26 is pivotally secured as at 27.

Suitable means such as the screw 28 provided with a pair of washers 29 and the lock washer 30 are provided to hold the head 24 in firm but yielding frictional engagement with the arm 19.

The lower end of the link 26 is provided with a laterally extending hook 31 which is adapted to engage within the aperture 32 in the lug 33 which projects upwardly from a bracket 34 secured to the upper edge of the lower sash 12. A second lug 35 suitably spaced from the lug 33 also extends upwardly from the bracket 34 and is cut away as at 36 to provide the requisite clearance to allow the hook 31 to be engaged or disengaged from the aperture 32. It will be noted that the lug is cut away so as to form an arcuate face which terminates at its upper extremity in a projecting shoulder 37 for a purpose which will hereinafter appear.

Referring to Fig. 1 of the drawing, the dotted line showing of the parts indicates the window sash 12 in closed position and from the relative positions of the brackets 17 and 34 it will be seen that the adjustable arms 19 and 26 will occupy an inclined position 110 when engaged with said brackets. When the sash is tilted from the vertical dotted

line position the arm 19 will pivot on the pin 18 and link 26 will pivot on the hook 31 and as the sash moves from the dotted line position the link 26 will move behind the projecting shoulder 37 which will effectually prevent the withdrawal of the hook except when the window sash is entirely closed. The parts are so proportioned that only a comparatively slight movement of the window to the open position is necessary to lock the link 26 within the bracket.

It will thus be seen that the window can not be opened from the outside by any unauthorized person after it has been moved 15 to an open ventilating position. In the assembly of the parts the lock washers are placed under sufficient tension to hold the window securely in any adjusted position in which it may be placed, without necessitating any further tightening of any bolts, nuts 20 or screws. Likewise due to the presence of the lock washers, the parts are held under a frictional spring tension which permits them to be moved by merely pulling the window to 25 the desired position without having to exert an undue amount of force.

It will be noted that the reduced end 23 of the head 24 is provided with a projecting boss 40 which is internally threaded to receive the screw 28. The inner washer 29 and the lock washer 30 are placed over this boss and it will thus be seen that the transverse or lateral strain produced when the head 24 is slid along the arm 19 is taken up by the 35 boss 40 and not by the screw 28.

Having thus described my invention what I claim as new and desire to secure by Letters Patent of the United States is:—

1. In a closure fastener, a straight slotted 40 arm, means comprising a yielding frictional connection to pivotally secure said arm to a window frame, a connecting link, yielding means to connect said link and arm in slid-

ing frictional engagement and detachable means to pivotally connect said arm to a 45 window sash.

2. In a closure fastener, a straight slotted arm, means comprising a yielding frictional connection to pivotally secure said arm to a window frame, a connecting link, yielding means to connect said link and arm in frictional engagement, detachable means to pivotally connect said arm to a window sash and means to prevent said means from being detached from said sash when the sash is in 55 an inclined position.

3. In a closure fastener means to secure the fastener to a window frame, a longitudinally slotted straight arm, a head provided with a reduced end adapted to be received in the slot of said arm, a threaded boss projecting from said reduced end, a lock washer on said boss, and means to engage said threaded boss to place said lock washer under tension whereby the head will be held in 60 yielding frictional engagement with said arm.

4. In a closure fastener adapted to hold a window in an inclined open position, a straight arm having a longitudinal slot 70 therein, a head provided with a reduced end adapted to be received in said slot, a threaded boss projecting from said reduced end, a link pivotally mounted on said head, a bracket adapted to be secured to the window 75 sash, said link and bracket provided with co-operating detachably engageable members, a lock washer on said boss and means to engage said threaded boss to place said lock washer under tension whereby the head will 80 be held in yielding frictional engagement with said arm.

Signed at New York in the county of New York and State of New York this 17th day of November A. D. 1921.

JACOB WEBER.
